Primary Examiner — Jennifer L Rempfer*Assistant Examiner* — Sarah A Nguyen(74) Attorney, Agent, or Firm — Eric Karich; Karich & Associates(57) CLAIM

The ornamental design for a laundry basket as shown and described.

DESCRIPTION

FIG. 1 is a perspective view of a laundry basket, showing the new design;

FIG. 2 is a front elevation view thereof;

FIG. 3 is a rear elevation view thereof;

FIG. 4 is a left side elevation view thereof;

FIG. 5 is a right side elevation view thereof; and,

FIG. 6 is a top plan view thereof.

The broken lines represent boundary lines for the purpose of illustrating portions of the laundry basket that form no part of the claimed design.

1 Claim, 6 Drawing Sheets(56)
